UNITED STATES PATENT OFFICE.

CHARLES C. LANE, OF LOS ANGELES, CALIFORNIA, ASSIGNOR TO LANE MILL & MACHINERY CO., OF LOS ANGELES, CALIFORNIA, A CORPORATION OF CALIFORNIA.

CHILIAN MILL.

1,264,532.

Specification of Letters Patent. Patented Apr. 30, 1918.

Application filed January 14, 1914. Serial No. 812,162.

To all whom it may concern:

Be it known that I, CHARLES C. LANE, a citizen of the United States, residing at Los Angeles, in the county of Los Angeles and 5 State of California, have invented certain new and useful Improvements in Chilian Mills, of which the following is a specification.

This invention relates to that class of mills 10 for crushing ores and recovering precious metals therefrom known as Chilian mills of the type shown in my Patent No. 1,082,960, dated Dec. 30, 1913.

An object of this invention is to provide 15 a Chilian mill in which the frame for carrying the rollers of the large diameter required for such mills can be constructed of sections that may be easily packed over mountain trails and can with facility be assembled to produce substantially a circular 20 periphery, and which frame will have sufficient strength to withstand the great strains to which such a frame is liable, and to permit jacking up when necessary for replacing 25 roller tires and the like without disassembling the mill.

An object of the invention is to provide 30 a construction whereby the momentum of the weight tank will be applied in the most direct and forcible manner to the crushing rollers and to so construct such appliance that it may be built in place and will accommodate the rollers in the most convenient manner, at the same time making provision 35 for centering the frame of the mill relative to the pan without liability of cramping.

Another object of the invention is to provide 40 a Chilian mill with a central pivot for the frame which will permit a slight tilting and a universal movement of the frame about the pivot so that whenever the crushing rollers pass over large pieces of rock or the like the mill will accommodate itself 45 thereto, thus preventing lateral strains that might otherwise occur upon the center shaft.

Still other objects of the invention are to provide a construction of minimum height having great compactness and stability when 50 assembled in position for operation, and to attain maximum efficiency with minimum power.

A further object of the invention is to provide such a mill with convenient and ef-

fective means for indicating to the operator 55 when the mill is being overfed.

The present mill is adapted to be equipped with the roller-adjusting means shown in my said patent, but the application of such means to the mill will be understood without detail illustration.

The invention may be carried out in various forms.

The important features, capabilities and advantages of the invention will become apparent from the subjoined detail description.

The accompanying drawings illustrate the invention.

Figure 1 is a top plan of a mill showing 70 one embodiment of the invention, the same being broken away in part for clearness of illustration.

Fig. 2 is a sectional elevation of the same on line x^2-x^2 , Fig. 1.

Fig. 3 is an enlarged fragmental broken detail illustrating one form of construction of the collars.

Fig. 4 is a reduced perspective of the mill, omitting the hopper.

Fig. 5 is a reduced perspective of the mill as shown in Fig. 4, but viewed from the opposite side and at a lower level than in said Fig. 4.

Fig. 6 is a perspective of parts of the mill 85 viewed from the same level as in Fig. 4 and further omitting the carriage and rollers.

In Figs. 3 and 4 the construction of the collars is shown in a general way; it being intended to make the collars of reinforced 90 concrete, wood, iron or other material as may be most convenient where the mill is to be installed.

In the embodiment shown a monolithic base 1 formed of reinforced concrete has an 95 upwardly extending portion 2 at one end to form bearings for a pulley 3 which may be connected to be driven by any suitable source of power, and which by means of suitable gearing connections 4 is adapted to drive a 100 spur pinion 5. Most of the remaining part of the base 1 co-operates with and forms a part of the mill proper having two annular concentric walls 6 and 7 extending upwardly, inclined from one another, and 105 forming an annular crushing channel or pan in which is positioned a track composed of sections 8 that are suitably anchored in

such a manner in a sectional anchoring plate 9 formed in the concrete base 1 as to leave an outer annular depression 10 adjacent to the wall 7 this depression being adapted to contain mercury as is customary in the practice. The contents of the annular depression 10 may be drawn off when desired by a suitable outlet 11 discharging into a receptacle 12 formed in the base 1 outside of the annular wall 7. (See Fig. 1.)

One side of the outer annular wall 7 is cut away almost down to the mercury bath; said base, at the recess thus formed being provided with suitable stanchions 13, two being shown in the present instance, which coöperate with the edges of the main portion of the wall 7 to support wall sections 15 between them. On top of these wall sections 15 are secured pans 16, one for each wall section 15, and above each of these pans a screen 17 is provided. As the ore which is crushed in the crushing pan between the walls 6 and 7 is passed around to the recess in the wall 7, the pulp which rises above the upper edges of the screen 17 will overflow and pass through the screens and over the pans 16 from which it can be conveyed to any suitable sluice or onto amalgamating plates. The screens will prevent large and light substances such as floating wood or the like, from passing on to the pans 16. In some instances the pans will be provided with amalgamating plates and in some cases no amalgamating plates will be used.

Centrally of the annular walls 6 and 7 the base 1 is provided with another upward extension 18 on which is provided a guide member such as the socket member 19 having a vertical bore adapted to receive a pin 20. The socket 19 is provided with a suitable lubricating chamber 21 formed by enlarging a portion of its bore. The pin 20 is provided with a ball 22 fixed to its upper end, and shown as of slightly larger diameter than said pin. A centrally-raised girder plate 23, which is normally horizontally disposed, is provided, having a central opening 24 which is of less diameter than the diameter of the ball 22, but of greater diameter than the pin 20, which extends downward through the opening 24, on the rim of which its ball 22 rests being secured against displacement by means of a cap plate 25 held in place by suitable means as bolts, and having a central concaved depression which fits over the ball 22, forming with the plate 23 a socket for the ball. A universal joint is thus formed permitting universal movement of the plates relative to the pin. The cap plate 25 has a central oil hole 25' through which lubrication of the pin is effected. The pin works freely up and down in the bore of the socket member 19 and holds in true central position the girder plate 23 which forms a central connection

for radial frame members such as the girders 26 that extend radially outward; there being in the present instance six such girders spaced apart symmetrically to permit rollers 27 to be mounted between each two successive girders. The girders 26 are substantially of equal length so that a practically circular rim 28 may be secured to their outer ends. The rim 28 is built up of two layers of separately constructed arched sections 29 overlapping at their ends, and secured together by means of bolts 30, or the like. The outer periphery of the circular rim 28 is turned down so that spur toothed segments 32, placed end to end, may be bolted or otherwise secured to such periphery to form a continuous annular toothed periphery adapted to mesh with the spur pinion 5. In this way the difficulty of forming a true circular rim of great diameter with steel or other metal is avoided and yet a knock-down toothed rim of great strength is provided.

Secured by means of bolts or the like on the upper edges of the girders 26 inwardly of the circular rim 28 are two corresponding concentric polygonal crown collars 33, 33' which are twelve-sided in the present instance and which have adjacent parallel sides; alternate parallel sides thereof being positioned between each two adjacent girders 26. In Figs. 1, 2, and 3, each side of these collars is composed of wooden planks cut to different lengths to form stringers 34 and fillers 35 of which there are six layers, one on top of another, the stringers of each side being in the same horizontal planes with fillers of adjacent sides and interlocked at their ends with the stringers of said adjacent sides; the fillers and stringers of each side and the interlocked ends of the stringers of adjacent sides being suitably bolted together. The ends of the planks of each layer are mitered to give shape to the collars and to fit the ends of the fillers to the edges of the stringers. Each of the stringers of one collar is parallel with a filler of the other collar, and each pair of parallel members thus formed constitute radially aligned sides of the collar; and the bearings for the rollers are attached thereto.

The rollers 27 are arranged respectively between adjacent girders, and on supporting shafts 36 that are mounted respectively in bearings 37, 37, secured to the lower face of those alternate pairs of adjacent parallel sides of the collars 33, 33' that are positioned between adjacent girders 26. The parallel sides are provided with series of bolt holes *a*, in the present instance shown as extending through the lower four layers of planks only; there being small supporting blocks 38 spaced apart from one another and strips 38' provided instead of planks for the fifth layer from the bottom to support the top

layer. The spaces between the supporting blocks are provided to permit nuts to be inserted to receive the bolts *b* when screwed thereinto through the bolt holes *a*. This 5 series of bolt holes is provided so that the position of the bearings may be changed to obtain different crushing effects.

A series of distributing pipes 39 is provided, each pipe being secured to a girder 10 26 and having its lower end discharging in front of a roller 27 and having its upper end communicating with and receiving suitably reduced ore from a common hopper 40. A suitable launder 41 is provided to 15 convey the ore to be crushed to the hopper 40 from which it is conveyed by means of the distributing pipes 39 to the crushing rollers 27. If ore is fed too rapidly the rollers are raised thereby and provision is 20 made to notify the attendant of such over-feeding. To this end there is mounted on the inner face of the circular rim 28 a bell 42 having its edge above the upper surface of said rim. A signal member comprising 25 a rod 43, fixed to the upwardly extending portion 2, and a head 44 secured at its outer end is positioned at a level just above that at which the bell 42 is designed to revolve so as to be struck by the bell to sound 30 an alarm when the circular rim 28 to which the bell is fixed rises above a predetermined level, thus to warn the attendant that the ore is being fed too fast.

The weight tank to give the rollers the 35 required crushing weight having an annular chamber 45 to receive suitable weights 46, and a central opening 47 through which the hopper 40 is permitted to protrude, may be of any suitable construction and is supported by and may be suitably fastened to the annular collars 33 and 33' if desired.

It is understood that the number of rollers may be greater or less than shown in the drawing, and that the parallel sections between 45 which said rollers are mounted will correspond in number to the number of rollers provided. In the form shown, there are six rollers and the collars are twelve sided; while with three rollers the collars 50 would be six sided, four rollers eight sided, and so on.

Obviously, various changes and modifications in the details of construction may be made without departing from the general 55 scope of this invention.

I claim:—

1. In a Chilian mill, the combination of 60 a monolithic base having two annular concentric walls extending upwardly and outwardly and forming a crushing channel, with sectional anchoring plates embedded in the base, crushing track sections so formed and attached to the anchoring sections as to leave an outer annular depression 65 between the crushing track and the outer

wall, and means leading from the bottom of the depression to the outside of the outer wall for draining said depression.

2. In a Chilian mill, a monolithic base having a crushing channel, a crushing track anchored in the channel, there being a drained annular depression outside of the track and between the track and the outer wall, overflow pans secured on top of the outer wall and leading to the outside thereof; and a screen above each of the overflow pans. 75

3. In a Chilian mill, a monolithic base provided with an annular crushing pan and a central support having a vertical socket 80 therein; a normally horizontal girder plate having a central opening therein; a pin adapted to slide freely up and down in the socket and extending through and loosely fitting in the opening; a ball fixed to the pin 85 at the upper end thereof and being of a larger diameter than the pin and the opening in the girder plate; a cap plate secured to the girder plate and provided with a central part that fits the ball and together with 90 the girder plate constitutes a socket that allows a free rotary movement in all directions within the socket for the ball; girders extending radially from the girder plate; a plurality of bearings arranged in peripheral 95 and transverse relation to and above the crushing pan at the inner side thereof; bearings at the outer side of the crushing pan and respectively aligned with the first-named 100 bearings; shafts respectively mounted to rotate in the aligned bearings; crushing rollers respectively secured to the shafts and adapted to travel in the annular crushing pan with the ball as their common pivot so as to allow the girder plate to rotate in or out of horizontal position; and means to cause rotation of the girder plate without interfering with the free movement of the ball and the pin. 105

4. In a Chilian mill having a rotatable 110 frame the combination with crushing rollers carrying said rotatable frame, of means for indicating to the operator when said Chilian mill is overfed, said means comprising a bell fixed to said rotatable frame, a flexible rod 115 fixed to a stationary support, and a knocker at the end of said rod in position to engage said bell whenever said rotatable frame is raised a predetermined distance due to over-feeding. 120

5. In a Chilian mill having a weight tank, the combination with a stationary guide-member, of a rotatable frame having a central plate, girders secured to said central plate and extending radially therefrom, concentric collars secured to said girders on which said weight tank is positioned, a pin, and a ball fixed to said pin and being movably anchored in said socket, said guide-member being provided with a bore to re- 125 130 135

ceive said pin to prevent lateral movement of said rotatable frame but to permit tilting of said frame by means of said ball and socket connection, said pin being free to rise 5 out of said guide member with said frame whenever the rollers are raised by the material over which they pass.

6. A universally movable guide-member 10 for the rotatable frame of a Chilian mill comprising a stationary guide-member, a plate having a raised portion and an opening in the center of said raised portion, said plate being secured to the center of said rotatable frame, a pin, a ball of greater diameter than said opening fixed to said pin, said pin being adapted to pass through said opening; and a second plate having a concaved recess; said second plate being fixed to said first-mentioned plate and adapted to anchor 15 said ball between said concaved recess and the pin of said first-mentioned plate, said

guide-member having a bore to receive said pin whereby to prevent lateral movement of said rotatable frame but to permit tilting and up and down movement of said frame 25 by means of said ball and socket and pin connection.

7. In a Chilian mill having a rotatable frame, the combination with crushing rollers carrying said frame, of signal means 30 carried by said frame, and stationary means above the normal level of said signal means to contact with the signal means and give a signal when the frame is raised above a determined level.

In testimony whereof, I have hereunto set my hand at Los Angeles, California, this 8th day of January, 1914.

CHARLES C. LANE.
